UNITED STATES PATENT OFFICE.

EDWARD MAURER AND JAMES G. VARLEY, OF CLEVELAND, OHIO.

CLOTHESLINE HANGER.

Application filed October 18, 1924. Serial No. 744,467.

This invention relates to a clothes line hanger of the type comprising a frame adapted for securement to a post or a building and provided with a pulley over which the clothes line travels.

The object of the present invention is to provide an improved clothes line hanger of the type described wherein the pulley is provided with an eccentrically arranged spiral groove into which the clothes line may be thrown by a lateral movement so as to cause the line to be caught and pinched by a cam-like action between said eccentric pulley portion and a suitably formed portion 15 of the supporting frame.

Further objects of the invention are in part obvious and in part will appear more in detail hereinafter.

In the drawing, which represents one suitable embodiment of the invention, Fig. 1 is a side elevation of my improved clothes line hanger; Fig. 2 is an edge view thereof; Fig. 3 is a detail sectional view through the main pulley groove; and Fig. 4 is a detail side elevation with parts broken away and in section.

Referring to the drawing, 1 represents the pulley supporting frame which preferably is of sufficient length to enable the housewife or maid to conveniently suspend the frame from a post or building at the proper height without the use of a stepladder or the like. To this end, the supporting frame, which is here shown as an elongated flat metal bar, is provided near its upper end with a suitable aperture 2 to receive a nail or hook, which method of securement not only enables the bar to be readily removed after use thereof, if desired, but also enables 35 the bar to assume various angular positions to conform to the location of other hangers or points of securement of the line. Usually, when the clothes line is in use, the hanger will assume a substantially horizontal position at approximately the height of the supporting nail or hook.

The lower end portion of the bar is formed as an open-ended offset loop or return bend 40 within which is journalled a pulley 4 mounted on a rivet secured in the loop side portions. The extreme lower end of the bar is curved inwardly, as at 6, so as to partially close the loop and thereby normally prevent

the accidental escape of the clothes line. This curved portion may be sufficiently 55 moved, however, or is sufficiently spaced from the main bar portion, to enable the clothes line to be easily inserted into and removed from the loop. To apply the clothes line to the pulley 4, the housewife or maid 60 need only loop the line and pass the loop over the inwardly extending curved portion 6. This may be easily and conveniently done without the use of a stepladder or the like, as it is not necessary for her to reach 65 with her hands the supporting nail or hook or even the pulley 4. The clothes line may, therefore, be conveniently supported at a greater height than has heretofore been possible.

The pulley 4 is provided, in addition to the usual annular groove 7, with one or more eccentrically arranged, spiral grooves 8, two such grooves being here shown. By a simple lateral movement, the clothes line travelling 75 along the annular groove may be thrown into one of the spiral grooves 8 and caught and pinched by a cam-like action between the eccentric pulley portion and the frame bar. In the present embodiment, said bar at the 80 top of the offset loop is provided with an outwardly pressed portion so as to provide a shoulder 9 which effectively co-operates with either of the spiral, eccentric pulley grooves in holding the clothes line fastened 85 in the hanger.

What we claim is:—

A clothes line hanger, comprising an elongated flat bar provided at one end with means for suspending it from a support and at its 90 opposite end bent back upon itself to form an open loop, the free end of said loop being bent toward the body to restrict the opening to said loop, a pulley journaled between the side members of said loop and 95 provided with a recess in its flange adjacent the body, said body being bent outwardly adjacent the pulley flange to form a recess in which the rope end lying in the flange recess of the pulley is held by tension on the 100 rope.

In testimony whereof we hereby affix our signatures.

EDWARD MAURER.
JAMES G. VARLEY.
